ROTOR FOR A HELICOPTER TOY

Uwe C. Seefluth, Haus Kronos, Seestrasse,
2409 Klingberg, Germany

Filed Jan. 31, 1972, Ser. No. 222,447

Term of patent 14 years

Int. Cl. D21—01

U.S. Cl. D34—15 KK

FIG. 1 is a bottom perspective view of a rotor for a helicopter toy showing my design;

FIG. 2 is a top plan view thereof;

FIG. 3 is a bottom perspective view of another embodiment thereof;

FIG. 4 is a top plan view of FIG. 3;

FIG. 5 is a bottom perspective of still another embodiment thereof; and

FIG. 6 is a top plan view of FIG. 3.

I claim:

The ornamental design for a rotor for a helicopter toy, as shown.
